ELECTROTYPE PLATE AND METHOD FOR MAKING THE SAME

Rowland Buckler, Chicago, Ill.

Application October 5, 1935, Serial No. 43,792
Renewed April 11, 1938

12 Claims. (Cl. 22—209)

My invention relates to means and methods of producing electrotype plates and the like, and my main object is to produce a plate which is inherently firm throughout, whereby to withstand the strains of prolonged use without becoming in any way deformed or deficient.

A further object of the invention is to produce a plate of the above character by casting it in the curved form required for mounting it on the press cylinder, whereby to eliminate the factor of stretch contended with in plates formed by the bending process.

A still further object of the invention is to employ a novel method for casting the plate, whereby to eliminate surface deficiency, body porosity and undue shrinkage.

Another object of the invention is to provide a unique mold for the casting of the plate, the mold having peculiar structural and functional values conducive to the results contemplated above.

A further object is to provide an improved method and mold for casting metal.

With the above objects in view, and any others which may suggest themselves from the description to follow, a better understanding of the invention may be had by reference to the accompanying drawing in which—

Fig. 1 is a perspective view of a typical curved electrotype plate;

Figures 2, 3 and 4 are schematic cross-sections of the novel mold in three positions of use; and

Fig. 5 is a section on the line 5—5 of Figure 3. In the production of electrotype plates, two methods have generally been followed. By one method, the plate is cast flat and later given its curvature in a hot bender. By the other method, a mold of the required curvature is employed to cast the plate, this method having the advantage that stretch usually present in the plate formed by the bending process is eliminated.

Whatever the process employed for producing the conventional electrotype plate, failure develops during the use of the plate at one point or another, whereby to render the printing imperfect. The failure is characterized by the collapse of the plate surface in regions where its resistance is poor by the inherent structure of the plate or as a result of pressure encountered during the printing action. Actually, the condition just described is due to the porosity of the plate through oxidation at the time it is cast, and to irregular places in the surface of the plate as caused by uneven shrinkage as it cools. Whatever

the methods may be which have been followed in the casting of electrotype plates, they seem to employ conventional practices already known in the casting art and unsuitable for the production of a perfect plate.

In contemplating the function of an electrotype plate, its main attribute is that it must be sufficiently hard to form a solid backing for the copper shell which forms its facing or printing surface. Ordinarily, a lead alloy is employed as the metal for the plate, since such metal lends itself more readily to uniting with the solder-coated inner surface of the copper shell. However, zinc or an alloy thereof is also quite suitable. In my method, I prefer to cast the plate in a curved mold, whereby to eliminate at the start the stretching factor. The theory of my mold and method therefore concerns itself with overcoming or eliminating porosity and shrinkage. Thus, by determining the causes of these factors and creating a means and method whereby these causes are diverted from the plate as it is being cast, a product having desirable qualities and no defects may be obtained.

Porosity in the conventional electrotype plate is the result of pouring the molten metal directly into the cavity in which the plate is to be cast or in such a manner as to reach the cavity in a turbulent or agitated state. Obviously, the molten metal absorbs a considerable amount of oxygen by its passage into the mold, and such absorption is increased where the metal within the mold is agitated by the incoming stream. The oxide compound formed within the mold is prevalent throughout the casting, making the plate porous. It is therefore seen that a plate so cast is not actually solid, as it contains innumerable trapped air and gas pockets, and is subject to breaking down in portions of its surface as pressure of use is applied.

Secondly, a plate made by conventional methods contends with the factor of uneven shrinkage. One reason for such shrinkage is poor conductivity of heat in the metal from which the mold is made as the plate is being cast and begins to cool. In other words, with the mold heated and of ordinary metal—such as iron—more heat may occur at one point than another, such heat being unevenly transmitted to the casting, and therefore causing the plate to shrink faster in one region than in another. The result of this action is to cause low spots in the plate surfaces, so that the plate is not only defective by porosity from the casting process but also by the presence of irregular or uneven regions

in its surfaces. To counteract uneven shrinkage, the practice has been to hammer the plate from points on its back behind the low spots, so as to raise these even with the general surface.

5 In developing the novel mold I have corrected the above deficiencies by a peculiar mold construction and a different casting method. Thus, by specific reference to the drawing it is seen that the base 10 and the top 11 of the mold are mainly 10 of the same and part-cylindrical form suitable for the casting of the curved plate 12 indicated in Figure 1. It is seen that the base 10 is slightly sunken to receive the copper facing shell 13. However, in the region of the mold entrance 14, 15 it is seen that the mold base 10 first takes a slight incline 10a, and then has a considerable drop to form a trough 10b which rises along its outer side to terminate with a backward lip 10c along the entrance 14. At the opposite end, the 20 mold also takes a slight offset 10d, terminating with an upward and dilated trough 10e. It is seen that the origin points of the deflected portions 10a and 10d form the terminals of the actual plate mold, such terminals later defining the 25 lines along which the plate is cut off from the entire casting. It is seen in the section of Figure 5 that the sides of the mold top 11 have flanges 11a overlapping those of the base, such flanges resting on the copper shell 13 and holding 30 the same down. The mold top also has dowel lugs 15 depending into registering cavities in the base to keep the mold sections from shifting relative to each other. Clamps or other suitable securing means are provided, as is the usual practice 35 in the molding art, to make the mold rigid.

The novel mold is ready, as positioned in Fig. 2, for the molten plate metal to be poured in by way of the entrance 14. It may be assumed that the metal on its way to and entering the 40 trough 10b will draw and absorb a certain amount of air. This air, being lighter than the metal, will rise through the same as the level of the metal gains height in the trough and escapes through the entrance 14 quite in the same manner 45 as bubbles rise and escape from a container of water when more water is added from above. However, what air cannot escape through the entrance 14 will become lodged immediately under the top of the mold, there combining with 50 the metal to form particles of slag or dross, which is an oxide of the metal in the trough.

In Figure 2, the body of liquid metal in the mold has reached its maximum height, and in order to permit more metal to be poured in, I cause 55 the mold to be rocked downwardly toward the right, continuing to pour the molten metal into the entrance 14. It will now be evident that the metal in the lower part of the trough 10b assumes a force or forms a head toward creating a flow 60 into the plate cavity of the mold. As this occurs, the slag or floating oxide found at A in Figure 2 is caused to move forward and keep ahead of the metal flow, as indicated in Figure 3. This flow being simply a transfer from the trough 10b 65 into the plate cavity without any agitation or absorption of air in transit fills the mold cavity without forming the objectionable slag, so that the faces of the casting are purely of the plate metal and not converted into the oxide. The mold is 70 further rocked to the position of Figure 4 in order to finish the process, the metal rising through the trough 10e, with the layer of slag on the surface.

Two factors contribute to the smooth flow of 75 the metal through the mold, one being the fact

that the mold is heated and made of a metal having a rapid rate of heat conductivity, such as bronze, and the other that the rocking of the mold promotes the motion of the metal by gravity. Thus, the mold is uniformly hot before pouring begins, and the rocking action is gradual, although it will be understood that the entire process is necessarily brief in order that the metal remain in the uniform fluid state as it fills the mold. Also, the special form of the mold has an 10 influence in this respect by the provision of the terminal troughs 10b and 10e. It is possible that the metal in the trough 10b may have more or less porosity when the pouring has been finished, since no further flow from the trough is had; also, 15 the metal in the trough 10e may have absorbed some air by its contact with the outlet and also suffered a change from the slight cooling effect occasioned by such contact. However, the metal in the plate cavity is between the two troughs and 20 therefore confined where no air contact occurs. It may consequently be assumed that the metal in the plate cavity is of uniform density and smooth texture.

Another factor taken into consideration in the 25 design of the mold is that of shrinkage. Ordinarily, shrinkage is allowed for by dimensioning the mold cavity accordingly, and it may therefore be assumed that the plate will suffer a normal amount of shrinkage after it has cooled. 30 However, the fact that the mold is made of bronze or other metal having a rapid rate of heat conductivity assures the uniform heating of the mold along the plate cavity and therefore the uniform shrinkage of the plate. A further characteristic 35 of shrinkage is that its rate is proportionate to the cooling time of the casting. Therefore, it is expedient that the plate cool quickly in order to suffer as little shrinkage as possible. By means of the novel mold, the metal in the region of the 40 plate cools more rapidly than that of the casting in general, since the relatively larger bodies of metal in the troughs 10e and 10b take so much longer to cool. By this analogy it is evident that the shrinking rate of these bodies will be greater 45 than that of the metal in the plate cavity, and that the plate will therefore have relatively less shrinkage than its terminal enlargements. Another factor helpful in cooling the metal of the casting more rapidly is that the metal of the 50 mold is relatively cooler both at the start and afterwards than the metal of the casting, so that the mold itself is a cooling influence on the latter. Finally when the casting has cooled, it is a simple matter to saw the terminal enlargements away from the cast plate and transfer 55 them to the melting pot.

It will be evident from the above description that I have provided a novel mold and process which make it possible to produce a firm, solid and smooth electrolyte plate. Not only is the peculiar design of the mold essential to procure a desirable plate as an intermediate element formed by the uniform action of the molten metal in a confined state, but the end portions of the mold 60 also serve as guards to retain such influences as would change the balance or prejudice the uniformity of the process. The latter is, at the same time, of extreme importance since it procures the shifting of the undesirable slag or dross 65 in a forward direction to meet the air in the unfilled portion of the mold and gather even more, to be removed finally to a zone distant from the plate cavity and where quality of the metal is of no concern. Moreover, the process is significant 70 75

by the gradual fall or rocking movement of the mold whereby to create a pressure or head for the metal going into the plate cavity without agitation or air contact, such flow coming from the bottom of the reservoir in which the metal initially accumulates. Finally, it will be evident that the novel mold is built along lines of extreme simplicity, making it inexpensive to produce and operate.

10 While the novel means and method have been described as applied to electrotype plates, the same are equally applicable to stereotype plates and any other articles for which the novel casting process and equipment are suitable, and it 15 is understood that I am including all such articles as coming within the scope of the appended claims.

I claim:

1. A mold comprising a base formed with upwardly extended end portions, one of such end portions having a return bend formed thereon to overlie a portion of said base, and a top for said mold adapted to be supported on said base and spaced centrally therefrom, the ends of said top 25 terminating short of said end portions to provide at one end a space between the same and the free edge of said return bend to form an entrance to the mold and to provide at the other end a space adjacent the opposite end of the 30 mold as a final gate cavity therefor.

2. A mold for casting molten metal, said mold being closed at the top and sides and open at both ends, one end being normally positioned on a lower plane than the other end, said molds 35 being adapted to be tilted gradually to position both ends on the same horizontal plane, means for continuously supplying molten metal to said lower end during the entire tilting operation to cause said metal to rise progressively in said mold to fill the same, and an open extension on said 40 second named end of said mold, said extension being positioned above the plane of said mold.

3. A mold for casting molten metal, said mold being closed at the top and sides and open at both ends, one end being normally positioned on a lower plane than the other end, said mold being 45 adapted to be tilted gradually to position both ends on the same horizontal plane, and means for continuously supplying molten metal to said lower end during the entire tilting operation to cause said metal to rise progressively in said mold to fill the same, said mold being arcuate in section.

4. The structure of claim 3, and an open extension on said second named end of said mold, said extension being positioned above the plane of said mold.

5. The structure of claim 2, and said means for supplying molten metal to said mold comprising a trough having an open communication with said first named end of said mold.

6. The structure of claim 3, and said means for supplying molten metal to said mold comprising

a trough having an open communication with said first named end of said mold.

7. The structure of claim 3, and said means for supplying molten metal to said mold comprising a trough having an open communication with said first named end of said mold, and an open extension on said second named end of said mold, said extension being positioned above the plane of said mold.

8. The method of casting metal into an upwardly inclined mold cavity comprising the pouring of the molten metal into a trough having an open communication with the lowest point of said mold cavity, tilting said trough and mold jointly while continuing to pour metal into said trough 10 to cause said metal to rise in said cavity up the incline towards the highest point thereof until said cavity is filled and stopping said pouring and tilting when said highest point and said lowest point are on substantially the same horizontal plane.

9. The method of casting metal into an elongated and arcuate mold cavity which is arranged to have one end thereof higher than the other, comprising the introduction of the molten metal 25 into substantially the lowest point thereof, tilting said mold continuously as said metal is introduced to cause said metal to rise in said cavity up the incline thereof towards the highest point of said cavity until said cavity is filled, and stopping said 30 tilting and the introduction of said metal when said highest point and said lowest point are on substantially the same horizontal plane.

10. The method of casting metal into an elongated and upwardly inclined mold cavity, comprising introducing said molten metal into substantially the lowest point of said mold, tilting said mold continuously while continuing to introduce metal to said lowest point to cause said metal to rise in said cavity towards the highest point of said mold until said cavity is filled, and stopping the introduction of metal and said tilting when said highest point and said lowest point of said mold are on substantially the same horizontal plane.

11. The method of casting arcuate metal plates with a minimum shrinkage factor, comprising the forming of the actual casting as a medial unit, forming terminal units of considerably greater cross section than said medial unit on either end of said medial unit, and positioning both of said terminal units on a plane above that of said medial unit.

12. A mold comprising an initial portion into which the metal is poured, a medial portion for the actual casting, said medial portion being of arcuate section, a final chamber for an extra casting portion, said initial portion and final chamber being of considerably greater cross section than said medial portion, and both said initial portion and final chamber being positioned on a plane above that of said medial portion.

ROWLAND BUCKLER.
